UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 12,980, dated May 20, 1882.

Application filed April 22, 1882. Term of patent 3½ years.

To all whom it may concern:

Be it known that I, WILLIAM McCALLUM, of Yonkers, in the county of Westchester and State of New York, have invented a new and original Design for Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

B is a circular flower-like figure with small sharp projections around it, from which projects, on one side, the branch a, bearing leaves, sprays, and flower-like figures. From the center of this flower figure B starts a stem bearing buds and leaves, and running upward until it expands into the flower figure A, somewhat resembling a tulip, from which in turn runs a leafy stem, which branches off on one side, and bears at its end the circular flower-like figure

E, apparently growing out of a cluster of leaves. From the same branch, extending from the figure A, grows toward the left a 25 deeply-indented flower-like figure, D, with star-like center, and the main portion of the branch, running onward, terminates in the figure C, which resembles a cluster of circular flowers surrounded by leafy foliage. The repetition of the figures already described upon the background forms the design.

I claim—

1. The design for carpets, consisting of the figures B and a, substantially as shown. 35
2. The design for carpets, consisting of the figures A, D, E, and C, substantially as shown.
3. The design for carpets, consisting of the figures B a A E D C, substantially as shown.

WILLIAM McCALLUM.
